United States Patent Office.

NOAH POMEROY, OF HARTFORD, CONNECTICUT.

Design No. 3,006, dated April 21, 1868.

DESIGN FOR A CLOCK-CASE.

The Schedule referred to in these Letters Patent and making part of the same.

TO ALL WHOM IT MAY CONCERN:

Be it known that I, NOAH POMEROY, of the city of Hartford, in the county of Hartford, and State of Connecticut, have originated and designed a new Design for a Clock-Case, of which the following is a full, clear, and exact description, reference being had to the accompanying drawing making part of this specification, which drawing or photograph is a perspective view of my invention.

My invention or production consists of the combination of an octagonal top of a clock-case and a circular sash around the dial.

The top of the case, A, I construct of three-eighths of an octagon, while the sash, B, around the dial, is of a circular form, or a circle.

Clock-cases with octagonal tops have been before made, but in all such cases the sash has been of a corresponding shape. Circular sashes have also been made with circular tops to the cases. To break this similarity is partly the object of my design.

What I claim as new, and desire to secure by Letters Patent, is—
The design for a clock-case as herein set forth and shown.
